All vs.

UNITED STATES PATENT OFFICE.

ALONZO A. CASLER, OF MANSFIELD, OHIO.

DESIGN FOR AN UPPER RUBBING-DISK FOR WASHING-MACHINES.

SPECIFICATION forming part of Design No. 35,170, dated October 8, 1901.

Application filed May 27, 1901. Serial No. 62,177. Term of patent 3½ years.

To all whom it may concern:

Be it known that I, ALONZO A. CASLER, a citizen of the United States, residing at Mansfield, in the county of Richland and State of Ohio, have invented and produced a new and original Design for Upper Rubbing-Disks for Washing-Machines; and I do declare the following to be a full, clear, and exact description of the same, reference being had to the accompanying drawings, forming a part thereof.

My invention is a new and useful design for the upper rubbing-disk of washing-machines, the object of my invention being the production of a rubbing-disk of new and novel shape which will also perform its functions in an efficient and practical manner.

With this object in view my invention consists of a rubbing-disk of new and novel design, as described herein, and illustrated in the accompanying drawings, in which—

Figure 1 represents a top plan view of my rubbing-disk. Fig. 2 represents a bottom plan view, and Fig. 3 represents a vertical central sectional view.

My design for a rubbing-disk consists of 25 the central rectangular plate A, with central aperture, from which rises a tubular part, a circular band or rim B, removed from said central plate, the inclined ribs C in pairs on the under face of the said plate and rim and 30 inclined toward each other from the periphery of the rim to and overlapping the corners of the central plate, and the two sets of parallel and straight ribs D, crossing each other about the said tubular part and forming a 35 rectangular inclosure therefor.

I claim—

The design herein shown and described for an upper rubbing-disk for a washing-machine. 40

In testimony whereof I affix my signature in presence of two witnesses.

ALONZO A. CASLER.
